UNITED STATES PATENT OFFICE.

HENRI G. LEVY, OF SAN FRANCISCO, CALIFORNIA.

DESIGN FOR A LAMP.

Application filed January 3, 1922. Serial No. 6. Term of patent 3½ years.

To all whom it may concern:

Be it known that I, HENRI G. LEVY, a citizen of the United States, residing in the city and county of San Francisco, State of California, have invented a new, original, and ornamental Design for Lamps, of which the following is a specification, reference being had to the accompanying drawing, forming a part thereof.

I claim:

The ornamental design for a lamp as shown.

HENRI G. LEVY.

Witness:

LINCOLN V. JOHNSON.
